METHOD OF MAKING PAPER CONTAINERS

Cesare Barbieri, New York, N. Y., assignor to
 Dixie Cup Company, Chicago, Ill., a corpora-
 tion of Delaware

Application January 10, 1948, Serial No. 1,531

2 Claims. (Cl. 93—39.1)

1

This invention relates to paper cups or containers.

It is necessary that paper containers to be used for hot contents or liquids be formed of heavier or thicker material than those used for other liquids. This is sometimes accomplished by using a blank long enough to form a wall of double thickness or, in other words, to wrap twice around the circumference of the container. The extra material and added time required to form this cup or container materially increase the expense of manufacture.

An effort has been made to solve the problem and to provide a container suitable for hot liquids by using a blank of heavier material which is wrapped once around the bottom with the ends overlapped and secured together. This has not been found to be entirely satisfactory since the stiffer or heavier material tends to unwind or uncurl and to become unglued, this tendency being aggravated by the hot liquid. Furthermore, where the lower portions of the blank ends are overlapped and secured to the bottom, a gap or opening is formed between the outer wrapped edge and the periphery of the flange of the bottom, thus causing a considerable leakage. This necessitates rigid inspection and tests and results in waste of material and product.

Moreover, in the type of container in which the wall is tapered and a bottom having a flange is secured thereto, the bottom tends to slide upwardly in the container, due to the interengaging tapered surfaces, thus tending to cause leakage. This is particularly true since the flange of the bottom under pressure used to glue the flange to the wall becomes serrated or creased.

A further difficulty is encountered in the cup or container with the flanged bottom since the flanged bottom is not always properly centered in the conical or tapered wall of the container and an opening and consequent leakage may occur between the tapered bottom flange and the wall of the container. Also, due to the thickness or stiffness of the material used in the blank, the inturned end at the bottom of the container wall may become unglued and open up.

This invention has for its object to provide a container so constructed that the overlapping ends of the wall will be securely sealed and locked against separation from each other and will be securely and tightly sealed and locked to the outer wall of the bottom of the container.

Another object of the invention is to provide a container so constructed that the bottom will be securely and tightly sealed within the wall of

the tapered container and will be held securely against movement relative thereto.

Another object of the invention is to provide a tapered or conical container so constructed that the bottom will be securely and tightly locked and sealed in position in such a manner that the container wall will not uncurl or loosen up, causing leakage.

Another object of the invention is to provide a paper cup or container so constructed that the containers can be nested in a manner to facilitate ready separation of the cups from each other.

Another object of the invention is to provide a method or process of making paper containers, so worked out that the overlapping ends of the blank will be securely sealed and locked against separation from each other and will be securely sealed and locked to the outer wall of the bottom and, furthermore, so that the bottom will be securely and tightly sealed within the wall of the tapered container and will be held against movement relative thereto.

Further objects of the invention will appear from the following specification taken in connection with the drawings which form a part of this application, and in which

Fig. 1 is a plan view of a blank used in making the container constructed in accordance with the invention;

Fig. 2 is an elevational view illustrating in section a blank folded around a mandrel with the bottom held in place, this view illustrating the first step in the method of making the container;

Fig. 3 is a view similar to Fig. 2 showing the next step in the operation in which the bottom of the container wall is folded inwardly against the flange of the container bottom;

Fig. 4 is a view similar to Figs. 2 and 3 but illustrating the next step in the operation, showing the lower end of the container wall pressed and secured against the inner surface of the flange of the bottom;

Fig. 5 is a view similar to Figs. 2, 3 and 4 but showing the final step in the manufacture of the container and in which the wall of the container is rolled or pressed inwardly under great pressure against the upper edge portion of the bottom, thus sealing and locking the container wall and bottom against leakage;

Fig. 6 is an elevational view showing the completed container;

Fig. 7 is an enlarged sectional elevation showing the flanged bottom mounted in the container

with the flange extending downwardly, this view corresponding to Fig. 3;

Fig. 8 is a sectional elevation of the lower portion of the container in which the final operation has been carried out and the annular groove has been formed to press the wall of the container tightly against the upper edge portion of the bottom and the lower edge of the bottom has been beveled to facilitate nesting the containers, as shown in Fig. 16;

Fig. 9 is a sectional elevation similar to Fig. 7 but showing the bottom mounted in the container with the flange extending upwardly in the container and the wall of the container pressed inwardly and locked against the lower edge portion of the bottom;

Fig. 10 is a fragmentary sectional elevation showing, in exaggerated form, the overlapping ends of the blank and the adjacent portion of the bottom, this view being added for the purpose of showing the gap between the outer wall of the blank and the adjacent portion of the bottom;

Fig. 11 is a view similar to Fig. 10 but showing the parts in the position taken after the container wall has been rolled or pressed inwardly under great pressure against the outer edge portion of the bottom to lock these parts together and close the gap shown in Fig. 10;

Fig. 12 is a top plan view of a portion of the container constructed as shown in Fig. 9, illustrating the creased or serrated condition of the upwardly extending bottom flange due to the deformation of the paper in drawing the flange which is retained in its deformed condition by the pressure used in gluing or securing the bottom flange inside the container wall;

Fig. 13 is a longitudinal sectional elevation through the bottom portion of the container shown in Fig. 9 after the container wall has been rolled or pressed in annularly against the edge of the bottom;

Fig. 14 is a fragmentary sectional elevation, on an enlarged scale, showing the lower edge portion of the mandrel and container wall and bottom prior to the formation of the locking groove and bead in the wall;

Fig. 15 is a view similar to Fig. 14 showing, in exaggerated form, the locking groove and bead and adjacent portions of the container wall and bottom; and

Fig. 16 is a sectional elevation showing two containers in nested relation.

In the particular embodiment of the invention illustrated in the drawings, the container is formed from a blank 20, shown in Fig. 1, this blank having adhesive or glue along one end, as shown at 21, and along the bottom, as shown at 22.

In the particular embodiment of the invention illustrated in Figs. 2 to 8 and 14 to 16 inclusive, the blank 20 is folded around a conical mandrel 25 and around a bottom 26 having a downwardly extending tapered flange 27. It will be understood that the bottom is supported below the mandrel in any suitable manner as the blank is folded around the mandrel.

After the blank has been folded in the manner set forth around the mandrel and around the flange 27 of the bottom 26, the second step in the operation is carried out, as shown in Fig. 3. In this step the lower end portion 28 of the container wall is folded inwardly and upwardly around the flange 27, as shown at 29 in Fig. 3. This inturned end of the lower portion 28 of the container wall is then pressed and glued tightly

against the inner surface of the flange 27, as shown in Fig. 4.

It will be understood that after the end of the blank 20 having glue thereon, as shown at 21, is folded around the mandrel, the glued portion 21 will be held against and secured to the outer surface of the other end of the blank.

When the operation has been carried out to the extent hereinbefore described, there is formed between the outer lap 30 of the container wall and the outer surface 31 of the flange 27, a gap, shown in exaggerated form, at X in Fig. 10.

This invention has for its salient object to close the gap X and to securely seal and lock the wall of the container to the outer surface of the bottom flange 27 and against the upper outer edge portion of the bottom 26. Referring particularly to the embodiment of the invention illustrated in Figs. 1 to 8 and 13 to 16 inclusive, this is accomplished by forming an annular, inwardly extending bead 32 in the wall of the container at the point where the wall abuts the outer edge portion of the bottom 26. This annular groove or inwardly extending bead is formed by exerting heavy pressure, by a roller or suitable tool, against the outer surface of the wall opposite an annular groove 33 formed in the lower edge portion of the mandrel 25, thus pressing the material of the wall into this groove, stretching the material of the wall, and forcing it inwardly to close the gap X and press the wall of the container into tight sealing relation with reference to the flange 27 and the upper edge portion of the bottom 26.

It will be noted that the groove 33 in the lower edge portion of the mandrel has an arc approximately one-half of a semicircle and when the wall of the container is grooved to form the bead 32, approximately one-half of the bead is disposed above the plane of the top 26 of the bottom and the other half is disposed below said plane and extends into the flange 27 of the bottom.

Under this heavy pressure the gap X, shown in Fig. 10, is closed, and the overlapping portions of the container wall are tightly held, sealed and locked against the container bottom. At the time this grooving operation is carried out the glue or adhesive has not dried and set and the paper is still moist and pliable. This operation effectively prevents leakage and the seal is made even tighter when hot liquid is placed in the container since the hot liquid will cause the bead 32 to tend to open up or widen, thus pressing the wall even more tightly against the upper outer edge of the bottom 26 and flange 27.

In order to permit the containers to nest in the manner shown in Fig. 16, the bottom edge of the container is bent inwardly, as shown at 34, so that this inwardly bent lower edge will rest on the bead 32 of the container disposed below the container nested therein.

If desired, the bottom of the container may be disposed in the manner shown in Figs. 9 and 13, namely, with the flange 27 extending upwardly instead of downwardly. In this case the lower end of the container wall is folded inwardly, as shown at 35, the upper edge being curled over to form a support for the container bottom 26. When this bottom, shown in Fig. 9, is drawn to form the flange 27, the material of the flange often becomes deformed, creased or wrinkled, as shown in Fig. 13, and due to this creased flange not being sealed tightly against the inner wall of the container the liquid sometimes escapes. In order to overcome this con-

dition and to further lock the bottom against movement in the container, the wall of the container has formed therein an annular, inwardly extending bead 36, similar to the bead 32 above explained. The bead 36 will be pressed into tight sealing and locking engagement with the outer edge portion of the bottom shown in Fig. 9, thus effectively sealing the contact between the lower edge of the bottom and the adjacent portion of the bottom flange and the container wall. In order to form the bead 36 the mandrel will have a groove similar to groove 33 opposite the portion of the wall where the bead is to be formed.

From the foregoing description it will be clear that the flanged container bottom and the inner surface of the container wall will be securely held in tight sealing and locking relation and that the bottom cannot move upwardly relative to the container and the outer overlapping end of the container wall will be effectively held in tight sealing relation against the outer and upper edge portion of the flange and bottom of the container bottom.

Although certain specific embodiments of the invention have been particularly shown and described it will be understood that the invention is capable of modification and that changes in the construction and in the arrangement of the various cooperating parts may be made without departing from the spirit or scope of the invention, as expressed in the following claims.

What I claim is:

1. The method of making a paper container which consists of wrapping a blank around a conical mandrel and around a flanged bottom, with the ends of the blank overlapping, securing the outer end to the overlapped portion of the wall and the container wall to the flange of the bottom, folding the bottom edge of the wall of the container so formed inwardly and upward-

ly against the bottom, and forcing the container wall inwardly above the flat surface of the bottom, inwardly at the periphery of the bottom and forcing the wall and flange inwardly below the plane of the flat bottom, thereby sealing the container wall to the bottom and locking the bottom in position.

2. The method of locking and sealing a container wall against the upper edge and flange of a flanged bottom secured within the container wall and held in position by an turned flange on the bottom of the container wall, which consists of forcing the container wall inwardly above, at and below the upper peripheral portion of the bottom and forming an inwardly extending annular bead depressed into the flange and over the peripheral portion of the bottom.
